UNITED STATES PATENT OFFICE.

HUGH C. LORD, OF ERIE, PENNSYLVANIA.

RAILROAD TIE.

Application filed June 27, 1921. Serial No. 480,616.

To all whom it may concern:

Be it known that I, HUGH C. LORD, a citizen of the United States, residing at Erie, in the county of Erie and State of Pennsylvania, have invented new and useful Improvements in Railroad Ties, of which the following is a specification.

This railroad tie is designed to carry a maximum load with a minimum amount of metal to retain its engagement with the rail under the very severe jar and shocks to which it is subjected, to give a slight amount of elasticity, to afford a surface around which the ballast may be readily tamped and to provide a structure which may be readily put in place and locked in engagement with the rail.

The invention is illustrated in the accompanying drawings as follows:—

Fig. 1 shows a side elevation, partly in section, on the line 1—1 in Fig. 2.

Fig. 2 a plan view of the tie.

Fig. 3 a section on the line 3—3 in Fig. 1.

Fig. 4 a section on the line 4—4 in Fig. 3.

1—1 mark the rails. These are of ordinary shape provided with the flanges 1^a at their bottoms. The tie is formed of two tubes 2—2. These tubes are formed of bent metal plate with the meeting edges 2^a at the bottom. Each tube is provided with lips 3 which are struck up from the tops of the tubes and from the metal forming the tubes. These lips are of a shape to engage the flanges 1^a of the rails. The two lips 3—3 on each tube extend in the same direction and the lips of one tube extend in a direction opposite from those of the other tube, the two tubes being interchangeable but reversed in position as clearly shown in

Fig. 2. Each tube has two securing tongues 4—4 struck up of the metal in the sides of the tubes. As the tongues are struck up they form openings 5 and the tongues are inclined outwardly. In placing the ties in position the two tubes are arranged in position under the rails with the lips 3 at the edges of the flanges and the tongues 4 in initial engagement. The two tubes are then forced endwise forcing the lips 3 over the flanges with a spring grip and forcing the tongues 4 along each other so that the two tubes are locked together.

In order to prevent a sliding of the tubes one on the other so as to disengage them from the rails I provide the stops 6. These

are formed by a vertical slit and an indenture inwardly one side of the slit and outwardly at the opposite side of the slit and these are placed in the adjacent faces of the tubes so that as the tubes are forced endwise the slanting surfaces are in engagement and as they are brought to place the stops snap past the engaging faces, the protuberances of one nesting in the socket of the other and the opposing faces fully locking the tubes against a return or unlocking movement. If, however, it is desired to remove a tie a thin bar is placed between the tubes and they are sprung apart sufficiently to clear the stops 6. The tubes are then forced endwise bringing the lips 3 out of engagement with the flanges and the tongues 4 out of engagement so that the parts are removed.

I prefer to form the tubes of general rectangular shape, slightly elongated in a vertical direction, so that the completed tie will be nearly square and I prefer to round the corners sufficiently to give a slight elasticity to the tie. In the drawings a very slight rounding of the corners is shown but this may be increased if it is desired to increase the elasticity. Only a small amount of elasticity is desirable. It will be noted that this structure affords four vertical webs for carrying the load and in consequence the gauge of metal used may be comparatively light. It will also be noted that all parts are integral so that there can be no danger of the jar to which the tie will be subjected loosening any of the engaging parts.

What I claim as new is:—

1. In a railroad tie, the combination of two plates having rail flange engaging lips, the lips of one plate extending in a direction opposite to that of the other and adapted to be moved over a rail flange by endwise movement of the two plates relatively to each other; and automatic means locking the plates in engaging position as they are moved endwise into engagement.

2. In a railroad tie, the combination of two plates having rail flange engaging lips, the lips of one plate extending in a direction opposite to that of the other and adapted to be moved over a rail flange by endwise movement of the two plates relatively to each other; and means for locking the plates in engaging position, comprising in-

terengaging stops on the plates moved automatically into locking relation as the lips are moved into engagement.

3. In a railroad tie, the combination of 5 two plates having rail flange engaging lips, the lips of one plate extending in a direction opposite to that of the other and adapted to be moved over a rail flange by endwise movement of the two plates relatively to each other; and means for locking 10 the plates in engaging position comprising interlocking tongues on the plates moved into interlocking position as the lips are moved into engagement and inter-engaging 15 stops on the plates moved into locking relation as the plates are moved endwise and preventing a return or disengaging movement of the plates.

4. In a railroad tie, the combination of 20 two tubes having rail flange engaging lips on their upper sides, the lips of one tube extending in a direction opposite to that of the other and being adapted to be moved over a rail flange by endwise movement 25 of the two tubes relatively to each other; and means for locking the tubes together in engaging position comprising interlocking tongues on the plates moved into locking position as the lips are moved into engagement.

5. In a railroad tie, the combination of 30 two tubes having rail flange engaging lips on their upper sides, the lips of one tube extending in a direction opposite to that of the other and being adapted to be moved over a rail flange by endwise movement of the two tubes relatively to each other; and means for locking the tubes together in engaging position comprising interlocking 35 tongues on the plates moved into locking position as the lips are moved into engagement and inter-engaging stops on the tubes moved into locking relation as the tongues are moved into engagement and preventing a return or disengaging movement of the tubes.

6. In a railroad tie, the combination of 40 two plates; means formed integrally with the plates for locking a rail with the plates by an endwise movement of the plates relatively to each other; and means for locking the plates in engaging position comprising stops formed integrally with the plates and moved automatically into locking relation 45 as the first-mentioned means is moved into engagement.

7. In a railroad tie, the combination of 50 two plates; means formed integrally with the plates for locking a rail with the plates by an endwise movement of the plates relatively to each other; and means for locking the plates in engaging position comprising interlocking tongues formed integrally with the plates and moved into locking position

as the first-mentioned means is moved into 65 engagement.

8. In a railroad tie, the combination of 70 two tubes; means formed integrally with the tubes for locking a rail with the tubes relatively to each other; and automatic means for locking the tubes in engaging position as they are moved endwise into engagement.

9. In a railroad tie, the combination of 75 two tubes; means formed integrally with the tubes for locking a rail with the tubes by an endwise movement of the tubes relatively to each other; and automatic means formed integrally with the tubes for locking 80 the tubes in engaging position as they are moved endwise into engagement.

10. In a railroad tie, the combination of 85 two tubes; means formed integrally with the tubes for locking a rail with the tubes by an endwise movement of the tubes relatively to each other; and means formed integrally with the tubes for locking the tubes in engaging position comprising inter-engaging 90 stops on the tubes moved into locking relation as the tubes are moved into engagement with the rail.

11. In a railroad tie, the combination of 95 two tubes, means formed integrally with the tubes for locking a rail with the tubes by an endwise movement of the tubes relatively to each other; and means for locking the tubes together in engaging position comprising interlocking tongues formed integrally with the tubes moved into locking 100 position as the tubes are moved into position to engage the rail.

12. In a railroad tie, the combination of 105 two tubes having lips struck up from their upper sides, the lips of one tube extending in a direction opposite to that of the lips of the other tube and adapted to engage the flange of a rail as the tubes are moved endwise relatively to each other; tongues struck out of the sides of the tubes and adapted to interlock as the tubes are moved endwise for locking the tubes together; and stops struck out of the sides of the tubes and adapted to move into locking position as the tubes are moved endwise to engage 110 the flange of a rail.

13. In a railroad tie, the combination of 120 two similar plates arranged in parallel and reverse position relatively to each other and having means for engaging rail flanges by endwise movement of the plates relatively to each other; and means for locking the plates together brought into locking position by the endwise movement of said plates.

14. In a railroad tie, the combination of 125 two similar plates arranged in parallel and reverse position relatively to each other and

having means for engaging rail flanges by endwise movement of the plates relatively to each other; and means for locking the plates together brought into locking position by the endwise movement of said plates comprising interlocking devices and stops for holding the locking devices in position.

15. In a railroad tie, the combination of two tubes forming a support for the rail,

the tops of all the vertical walls of the tubes having rounded portions giving elastic support to the upper or supporting walls of the tubes; means for securing the tubes together; and means formed integrally with the tubes for engaging a rail.

In testimony whereof I have hereunto set my hand.

HUGH C. LORD.
